United States Patent Office

Des. 175,337
Patented Aug. 16, 1955

175,337

CHAIR OR THE LIKE

Alfred C. Dion and Henry J. Dion, Putnam, Conn.

Application June 14, 1954, Serial No. 30,979

Term of patent 3½ years

(Cl. D15—1)

FIG. 1

FIG. 2

FIG. 3

FIG. 4

INVENTORS
ALFRED C. DION
HENRY J. DION

Fig. 1 is a perspective view of a chair or the like, showing our new design;

Fig. 2 is a front view in elevation thereof on a reduced scale;

Fig. 3 is a view in side elevation thereof; and

Fig. 4 is a rear view thereof with the upholstery removed.

We claim:

The ornamental design for a chair or the like, as shown.
